UNITED STATES PATENT OFFICE.

BRUCE CONKLIN, OF WESTMINSTER, ENGLAND.

ROTARY ENGINE.

1,280,668.

Specification of Letters Patent. Patented Oct. 8, 1918.

Application filed June 4, 1915. Serial No. 32,177.

To all whom it may concern:

Be it known that I, BRUCE CONKLIN, a citizen of the United States of America, residing at Westminster, in the county of 5 Middlesex, England, have invented a new and useful Improvement in and Relating to Rotary Engines, of which the following is a specification.

My invention has reference to rotary 10 engines of the kind comprising a stationary inner drum having a plurality of rotary abutments and an outer rotary casing having a plurality of vanes the annular working cylinder being formed by the space between the drum and the casing.

The primary object I have in view is to provide an improved engine of the aforesaid type which while being simple in construction and positive in operation shall be 20 adapted to be employed as a prime mover actuated by steam compressed air or other expansible fluid or used as a compressor pump blower or exhauster.

Among the further objects of the invention 25 are to provide an engine of the above mentioned kind in which there shall be an entire absence of positively actuated valve mechanism for the distribution of the working fluid to provide improved means for lubricating the parts and generally to produce 30 an engine which shall be more efficient for the ends in view than devices of the kind as heretofore suggested.

With the aforementioned and other objects in view as may hereinafter appear or are incidental thereto the present invention in its broadest aspect may be said to contemplate within the scope of the appended claims a construction of the aforesaid kind 40 in which the inner stationary drum serves as a steam chest or working fluid chamber said working fluid being distributed through ports in the periphery thereof to ports in the outer rotating casing whence 45 it is conducted by suitable passages in said casing to the annular chamber to drive the vanes the exhaust of the fluid being effected through ports in the drum communicating with the exhaust passages therein. 50 By this feature of my invention considerable economies result due to a lessening of the usual condensation difficulties.

A further feature of my invention is that in normal running the ports communicating 55 with the expansion chamber always maintain their like character thus an inlet

port for the working fluid always remains an inlet port and an exhaust port always remains an exhaust port. The advantage of this construction in the case when steam 60 is the working fluid is manifest as the possibility for condensation is reduced to a minimum.

Moreover as a feature of my invention it will be seen that the exhaust ports are 65 entirely segregated from the inlet ports to the end that a proper and most economical temperature gradient may be maintained in this type of prime mover.

In order that my invention may be 70 readily understood and carried into effect by those skilled in the art to which it appertains I will now proceed to describe the same fully for which purpose reference is to be had to the accompanying drawings in 75 which:

Figure 1 is a sectional view of a rotary engine embodying my improvements taken substantially on the line *a—a* of Fig. 3.

Fig. 2 is a section—but drawn to a smaller 80 scale—taken along the line *b—b* of Fig. 1 illustrating the arrangement of the induction ports to the expansion chamber from the stationary drum.

Fig. 3 is a section—also on a smaller 85 scale—taken along the line *c—c* of Fig. 1 illustrating more especially the arrangement of the vanes, ports and the rotary abutments.

Fig. 4 is a section—on a smaller scale—90 along the line *d—d* of Fig. 1 illustrating the arrangement of the exhaust passages.

Fig. 5 is a detail view of the packing rings hereinafter described and the means for adjusting same. 95

Referring now to Figs. 1 and 2 the working fluid is normally made to enter a hollow drum 1 by means of a tubular shaft 2 supported rigidly at one end by means of the end bearing 3 and on the other end is 100 made to nest by means of the roller bearings 4 within a rotating casing 5 journaled at one end by means of roller bearings 6 on an end bearing 7 similar to end bearing 3 and on the other end of the casing by means 105 of a roller bearing 8 about the stationary drum shaft.

The fluid entering the hollow shaft 2 passes into the drum 1 and is distributed by means of the port 9 therein into the port 101 10 of the casing (Figs. 1 and 2) when these latter ports are in register as will happen in

the course of the rotation of the casing 5 with respect to the stationary drum 1. The fluid then passes by way of the elongated port 11 in the casing to the expansion or 5 working chamber 11¹ determined by the rotating vane 12 the rotary abutment 13 the stationary drum 1 and the inner wall of the rotating casing 5. The expansion of the fluid within the chamber 11¹ will continue till the vane 12 reaches and passes within the pocket 14 in the rotary abutment 13¹ when the position of the parts will be as shown by the vane 12¹¹ in the pocket of the rotary abutment 13¹ in Fig. 3. The 10 proper timing of the rotary abutments with respect to the vanes is obtained by means of the gear 15 (Fig. 1) attached to the rotating casing 5 engaging with a spur 16 which in turn engages with a gear 17 keyed to the 15 shaft of each of the rotary abutments.

When the rotary vane 12 reaches the position indicated at 12¹¹ in Fig. 3 practically the entire amount of the possible expansion of the fluid entering through the port 11 has 20 taken place in the chamber 11¹ and during this movement the exhaust of the previous working charge is being effected through the exhaust port 18 communicating with the duct 19 (see Figs. 3 and 4) when the port 25 20 on the rotating casing on further travel registers with the port 20¹ which in turn communicates with the passage 21 (Fig. 1) shown at the right hand of the stationary drum in Fig. 1 which passage 21 communicates with the annular passage 22 about the hollow shaft 2 on its way to the atmosphere at 23. The cycle of operations just 30 described is repeated as each of the vanes successively pass the rotary abutments. 35 In order to avoid any possibility of leakage taking place past any of the vanes I provide a packing strip 24 (see Fig. 1) pressed inwardly by springs 25 which nest within the portion 26 of the vane attached 40 to the casing 5 by means of the bolts 27. On the other hand I also provide packing rings 28 29 which are preferably split as shown and engage with the surface of the stationary drum 1 to overcome any tendency toward leakage on a lateral direction 45 to the face of the drum. These packing rings which are in the nature of piston rings I preferably hold in place by means of wires 30 (see Fig. 5) engaging the rings 50 28 29 circularly which wires are caused to cross each other near their ends and are led out of the rotating casing 5 into pockets 55 31 where by means of the nuts and washers 32 an abutment is formed for the springs 33 engaging with the walls of the pockets 31 to hold the rings 28 29 in tight engagement 60 with the stationary drum 1. By this construction the rings may be tightened to any desired extent to compensate for wear 65 or otherwise. Preferably the rings are in

several sections the joints as shown in Fig. 5 being located opposite the vanes and I may provide each section of ring with one or more projections taking into recesses in the casing to prevent shifting of the ring 70 sections.

In order to provide an efficient system of lubrication for the engine an oil inlet 34 is provided communicating with the oil ducts 35 whereby a suitable lubricant may 75 be caused to distribute itself to the gears and to the bearings and face of the rotary abutments and thence to the working cylinder or expansion chamber. It will therefore be seen that I have provided by my invention a very simple compact and efficient lubricating system for a rotary engine devoid of any kind of reciprocation or variable movement whatever. Moreover by means of the bolts 36 and the fact that I 80 have provided end shields 5 5¹ for the rotating casing the assembly and disassembly of the machine can be undertaken with the minimum amount of time and trouble. Furthermore in order to cut down the losses due 85 to windage I provide a shield 37 which gives a smooth and neat appearance to the engine and at the same time serves to lock in place the assemblage of bolts such as 26 used to 90 keep the vanes in place.

The operation of an engine embodying my invention is as follows: The working fluid entering the drum 1 communicates with the expansion chambers such as 11¹ (see Fig. 3) behind the vanes 12 12¹¹ 12¹¹¹ in their respective order of sequence and in advance 100 of the rotary abutments 13 13¹ 13¹¹. The direction of rotation of the outer casing 5 is in consequence clockwise as indicated by the arrows in the several figures. The timing of the induction of the working fluid corresponds with the relationship of the induction ports 10 on the rotating casing 5 and the ports 9 on the stationary drum communication with the internal steam chest 105 space. The relationship of these latter ports is indicated in Fig. 2. Turning now to Fig. 3 it will be seen that whereas the induction of the working fluid always occurs through the ports 11 behind the respective vanes the 110 exhaust for the respective expansion chambers behind the vanes always occurs through the corresponding exhaust ports behind the induction ports feeding such expansion chambers. Moreover the exhaust ports are 115 oppositely arranged with regard to the expansion chambers. The exhaust fluid travels parallel and external to the hollow intake shaft 2 to an outlet 23 to the atmosphere or 120 to the usual exhaust pipe.

Now it will be obvious that an engine constructed as above described may be caused to rotate in a counter-clockwise or reverse direction by admitting the working fluid through what are normally the exhaust pas- 125 130

sages and ports and exhausting through the aforesaid tubular shaft. A significant feature of the operation of the engine is that by providing an unequal number of vanes 5 with respect to the rotary abutments the turning moment is very much evened up. It will be seen that in the construction herein described the ports in the drum and outer casing are so disposed relatively to each 10 other as to produce between each two abutments in succession a working stroke or power impulse and exhaust of the previous charge and since there are three abutments and four vanes there will thus be twelve 15 power impulses per revolution of the rotary casing. By increasing the number of rotary abutments and vanes any desired number of power impulses per revolution may be obtained and it may here be pointed out that 20 as the surfaces of the abutments are in fluid tight contact with the inner smooth surface of the rotating casing said abutments will act as rollers to reduce friction and therefore the greater the number of abutments em- 25 ployed the steadier the engine will run as practically the whole weight of the rotating parts will be supported upon said abutments.

I may provide means whereby the effect 30 area of the induction and exhaust ports in the aforesaid drum may be varied so that on starting or when the load on the engine is increased the amount of high pressure working fluid may also be increased.

35 It will of course be apparent that with slight modifications the inner drum may form the rotary element while the outer casing is stationary, in which case the rotary abutments are carried by the outer casing 40 and the vanes by the drum.

I claim:

1. A rotary engine comprising a normally stationary drum having a plurality of rotary abutments and an outer rotating cas- 45 ing having a plurality of vanes wherein said drum and casing are provided with induction and exhaust ports and passages which as they register cause the working fluid to

be distributed from the drum to the working chambers of the engine and from the working chambers to exhaust and means for introducing working fluid to the interior of said drum. 50

2. A rotary engine comprising a normally stationary hollow drum having a plurality of rotary abutments and an outer rotating casing having a plurality of vanes, means for introducing the working fluid to the interior of said hollow drum, ports in the periphery of said drum whereby said working fluid is distributed to the annular working chamber of the engine and ports and passages in the outer rotating casing for the exhaust of the low pressure fluid. 55 60

3. A rotary engine comprising a normally stationary hollow drum having a plurality of positively rotated abutments and an outer rotating casing having a plurality of vanes, means for introducing the working fluid to the interior of said hollow drum, ports in the periphery of said drum whereby said working fluid is distributed to the annular working chamber of the engine and ports and passages in the outer rotating casing 70 75 for the exhaust of the low pressure fluid and means for maintaining a fluid tight joint between the moving parts.

4. A rotary engine comprising a normally stationary hollow drum having a plurality of positively rotated abutments and an outer rotating casing having a plurality of vanes, means for introducing the working fluid to the interior of said hollow drum, ports in the periphery of said drum whereby said working fluid is distributed to the annular 80 85 working chamber of the engine and ports and passages in the outer rotating casing for the exhaust of the low pressure fluid and means for maintaining a fluid tight joint between the moving parts and means for distributing a lubricant to the rotating parts. 90
